DEODORANT PUFF AND METHOD OF
MAKING SAME

Walter Langer, New York, N. Y.

Application May 28, 1937, Serial No. 145,185

12 Claims. (Cl. 132—78.5)

This invention relates to deodorant puff and method of making same. A puff embodying this invention is especially adapted for application to the skin so as to deposit on the skin a material having a deodorizing effect. In this connection the word "deodorant" is used in a broad sense as including substances which are anti-perspirants and act to prevent perspiration from occurring and as including substances which are odor removing in character and are adapted to remove odor from perspiration after it has occurred.

Heretofore deodorants have been made up in liquid or cream form or in powdered form. In either case it is necessary to have a suitable container such as a bottle for containing liquid, a tube for containing cream or a box for containing powder in order to carry the deodorant material. It is inconvenient, however, to carry such containers in a pocket book, for example, due to the bulk thereof and the likelihood of the deodorant material spilling out.

There has been a further defect in connection with deodorants which have heretofore been made and sold in that they are harsh in their effect and tend to irritate the skin. Likewise the chemicals which have been used heretofore, e. g., aluminum chloride, zinc chloride, etc., frequently have the objection of being injurious to cloth out of which the garments of the user are made.

It is a purpose of this invention to afford to the public a deodorant which is available in a much more convenient and desirable form than heretofore. According to one feature of this invention, a deodorant material is used in combination with what is referred to herein as a "puff." The puff may be of a soft and pliable material and should have numerous fibers extending from at least one side thereof. Various types of fabric such as fabrics made of cotton may be used and during the weaving or subsequent thereto the fabric should be caused to have numerous fibers extending therefrom. Alternatively a felted fiber mat may be used for the puff and may be manufactured in such a manner that the fibers on at least one side are relatively free and adapted to entangle a deodorant material and a powder thereon. According to this invention the puff carries a deodorant material and preferably a mixture of deodorant materials of the character below described and the deodorant material is carried as by mere entanglement with the numerous pliable fibers extending from the puff so as to be readily detachable from the fibers upon applying the puff to the skin. It is apparent

that according to this invention the deodorant is available in a new form and so far as I am aware the combination of a puff with a deodorant adapted to be readily removed upon patting or rubbing the puff on the skin is new in the art.

The advantages of a deodorant puff embodying this invention are many. In the first place, a deodorant puff embodying my invention can be readily made and sold and, as thus made and sold, afford individual applicators to the user. Anyone or more of such puffs may be removed from a box carried in a handbag and after use can be discarded. Moreover, individual puffs in individual containers may be marketed. As will be described more in detail below, there are several desirable ways of packing and using deodorant puffs embodying my invention.

A further feature of this invention resides in the use of a powdered base material in conjunction with a deodorant material and in combination with the foundation member for the puff. The powdered base material acts as a carrier for the deodorant material and enables the deodorant material to be readily detached from the fibers on the puff. Were it not for the powdered base material, the deodorant chemical could not readily be removed from the puff and the use of the puff would be inconvenient, would require severe application, and would involve waste of deodorant material. By the use of the powdered base material such difficulties are avoided.

Some powdered base materials are preferable to others. For example, I have found that the ordinary ingredients of face powder, e. g., talcum powder, magnesium carbonate, zinc stearate, clay, etc., become removable with difficulty from a puff when combined with deodorant materials. I have found that calamine is especially suitable as a powdered base material for use in combination with deodorant chemicals and a fibrous foundation member. This material, namely calamine, has the property of adhering to the fibers extending from the puff in a satisfactory manner and this characteristic in the calamine is not impaired when it is combined with the deodorant chemicals. It is desirable that the powdered base material, when used with the deodorant materials, adhere sufficiently to the fibers so as not to fly about excessively and so as not to become prematurely removed from the puff during shipment and storage. On the other hand, it is desirable that the powdered base material, together with the deodorant chemicals, be adapted for ready detachment from the fibers of the puff upon applying the puff to the skin so that the

powdered base material and deodorant material may be readily removed from the puff and deposited on the skin. As aforesaid, I have found, as a result of much experimentation, that calamine has the foregoing desirable properties and in a very high degree. In addition to calamine, zinc oxide may be used as a powdered base material, but it is somewhat less satisfactory than calamine. Zinc oxide is, however, distinctly superior to other powder materials, such as those materials hereinabove mentioned, which are commonly used in face powders. Moreover, calamine and zinc oxide are distinguished by a pronounced drying quality and are advantageous for this reason in a deodorant puff according to my invention.

Further features of this invention relate to the deodorant materials that are used. I have found that benzoic acid and salicylic acid are desirable 20 inasmuch as these substances exercise a deodorant effect on perspiration and are relatively non-irritating to the skin. Tannic acid, tannic acid salts, aluminum sulphate and zinc salts such as zinc sulphate and zinc sulpho-carbolate are also 25 desirable and, due to their action in precipitating the albumen of the skin, they have the property of preventing or reducing perspiration and of acting as deodorants in this manner. It is desirable to employ deodorant material part of which 30 is a substance that acts primarily to remove the odor of perspiration and another part of which is a substance that is an anti-perspirant and prevents perspiration.

Thus I have found it to be especially desirable 35 to use substances adapted to remove odor from perspiration such as benzoic acid and salicylic acid and mixtures thereof in combination with substances adapted to prevent perspiration such as tannic acid, tannic acid salts, zinc salts and mixtures thereof. Tannic acid salts such as tannoform (tannin-formaldehyde) are illustrative of tannic acid salts which may be used. Zinc salts such as zinc sulpho-carbolate, zinc sulphate, etc. are illustrative of zinc salts which may 45 be used.

While any of the deodorant materials above mentioned can be used alone, the use of one substance alone requires, to be effective for the purpose, the use of the substance in an amount which 50 is somewhat irritating to the skin. I have found that instead of using one substance as a deodorant material, several deodorant materials can be combined to advantage. For some reason the 55 combination of several deodorant materials is less irritating to the skin than a corresponding amount of one of the materials used alone. In preferred practice I employ a plurality of the substances above mentioned, e. g., benzoic acid, salicylic acid, benzoin, zinc sulpho-carbolate, oxyquinolin sulphate, etc., and a substance selected from tannic acid and tannic acid salts, and thereby afford a mixture which has a powerful 60 deodorant effect and which is not irritating to the skin. Moreover, these materials have the important advantage that they do not injure the fabrics such as silk, cotton, etc. out of which garments are made and do not injure the material out of which the foundation member of the 65 puffs is made.

The following are certain illustrative embodiments of this invention, the materials recited being in each case carried by fibers extending from a soft and pliable foundation member.

	Per cent
(1) Powdered base material selected from calamine, zinc oxide, and mixtures thereof-----	70 to 90 5
Odor removing substance selected from benzoic acid, benzoin, salicylic acid and mixtures thereof-----	½ to 5
Anti-perspirant substance selected from the substances tannic acid, tannic acid salts, zinc sulphate, zinc sulpho-carbolate, aluminum sulphate, oxyquinolin sulphate and mixtures thereof-----	10 2 to 15
(2) Powdered base material selected from calamine, zinc oxide and mixtures thereof-----	15 70 to 90
Benzoic acid-----	¼ to 2
Salicylic acid-----	¼ to 2
Zinc sulpho-carbolate-----	2 to 15 20
Substances selected from tannic acid, tannic acid salts and mixtures thereof-----	½ to 5

The manner of manufacturing a deodorant puff is also part of this invention. I have found that it is preferable to make a deodorant puff embodying this invention by mixing a powdered base material, such as calamine, zinc oxide, or a combination of these materials, together with the deodorant materials and making a semi-fluid mix thereof by the use of a volatile liquid. The resulting mixture may be somewhat like a thin paste and may be of varying degrees of fluidity. Accordingly, the mixture is regarded as best referred to as being semi-fluid in character. The semi-fluid mixture is applied to the puff in any desired manner, as by brushing or spraying it on the material out of which the puff is made, by pressing or stamping it into such material, or the like. After the paste has been applied, the liquid is caused to evaporate as by exposure to the atmosphere or mild heating in a drying oven, leaving the solids entangled with the fibers extending from the puff.

I have found that especially satisfactory results are obtained when the deodorant materials are caused to be in a state of partial solution in the volatile liquid used in making semi-fluid mixture. If the deodorant materials are caused to go wholly into solution the materials tend to form a skin on the fibers of the puff which makes it difficult to remove the materials from the puff. On the other hand, if the deodorant materials do not go into solution at all the materials do not penetrate into the puff sufficiently. Accordingly, it is a feature of this invention that the deodorant materials are caused to assume a state of partial solution in the liquid used in making the semi-fluid mixture that is applied to the puff so that the materials penetrate into the puff and, at the same time, are deposited thereon in such condition that they can readily be removed upon applying the puff to the skin.

A semi-fluid mix may be made using ingredients such as those hereinabove mentioned and a mixture of alcohol and water may be used as the liquid for forming the paste. The alcohol (ethyl alcohol) is a solvent for benzoic acid and salicylic acid. Other similar solvents and appropriate to the deodorant material used may be selected such as isopropyl alcohol, acetone, etc. By way of example, a semi-fluid mixture of calamine, benzoic acid, salicylic acid, tannic acid, zinc sulpho-carbolate, water and alcohol may be made up wherein the tannic acid and zinc sulpho-

carbolate are dissolved in water and the benzoic acid and salicylic acid are only partially dissolved by the alcohol and are substantially insoluble in the water. If, for example, one part of alcohol is used to three or four parts of water, the amount of alcohol is insufficient to dissolve all of the benzoic acid and salicylic acid, and about half of the benzoic acid and salicylic acid occur as finely-divided particles in the mix. When such a composition is made up in the form of a thin semi-fluid mix and is applied to a puff, the deodorant materials together with the calamine penetrate into the puff so that they become adherent to the fibers extending from the puff and at the same time can be readily removed upon application of the puff, after it has dried, to the skin. Part of the deodorant material such as the benzoic acid and salicylic acid will be carried as discrete particles on the fibers extending from the puff due to the fact that a considerable amount of these materials has not been dissolved. An additional part of the deodorant material including some of the dissolved benzoic acid and salicylic acid, together with dissolved tannic acid and zinc sulpho-carbolate becomes coated on the calamine base material which in turn adheres to the fibers of the puff. When a puff prepared in this manner is used, the deodorant materials either occurring as discrete particles or as a coating for the calamine are readily detachable from the puff, but at the same time they adhere thereto sufficiently strongly so as to not fall off prematurely.

The following are illustrations of formulas which I have found to be especially suitable in the preparation of a semi-fluid mix for application to a puff.

	Per cent
(1) Powdered base material selected from calamine, zinc oxide and mixtures thereof-----	10 to 30
Odor removing substance selected from benzoic acid, benzoin, salicylic acid and mixtures thereof-----	1/4 to 3
Anti-perspirant substance selected from tannic acid, tannic acid salts, zinc sulphate, zinc sulpho-carbolate, aluminum sulphate, and oxyquinolin sulphate-----	1 to 10
Liquid including water and a volatile solvent for the said odor removing substance-----	30 to 60
(2) Calamine-----	10 to 30
Benzoic acid-----	1/4 to 2
Tannic acid-----	1 to 5
Zinc sulphate-----	1 to 10
Water-----	30 to 60
Ethyl alcohol-----	20 to 40
(3) Zinc oxide-----	10 to 30
Benzoic acid-----	1/4 to 2
Salicylic acid-----	1/4 to 2
Tannic acid salt-----	1 to 5
Zinc sulpho-carbolate-----	1 to 10
Water-----	30 to 60
Ethyl alcohol-----	20 to 40

The puffs can be made of varying strength as by controlling the amount of semi-fluid mix that is applied to the foundation material for the puff or by controlling the dilution of the semi-fluid mix, or by controlling the proportion of deodorant materials in the mix.

Further purposes, features and advantages of this invention will be apparent in connection with the following description of certain illustrated

embodiments of this invention shown in the accompanying drawing, wherein:

Fig. 1 is a plan view of a sheet of material having fibers extending from the upper side thereof;

Fig. 2 is a perspective view of an individual puff having fibers extending from one side thereof;

Fig. 3 is a cross section of the puff shown in Fig. 2; and

Figs. 4 and 5 are cross sectional views of modified forms of puffs embodying this invention.

The figures in the drawing are not intended to show actual proportions but are largely diagrammatic. Referring to Figs. 1, 2 and 3, individual puffs such as the puff shown in Fig. 2 may be made from a sheet of material, e. g., from the sheet 10 shown in Fig. 1. The detail of the structure of the sheet 10 and of the puff shown in Fig. 2, is shown in Fig. 3. The fabric base 11 has numerous fibers 12 extending from one side thereof. This affords a soft and pliable foundation member for the puff having fibers extending therefrom which are adapted to carry deodorant material. As aforesaid, the material may be made of cotton, wool and the like and may be formed in any suitable manner as by weaving, felting, or the like. The individual puff may be round as shown in Fig. 2. A plurality of individual puffs may be stamped or otherwise cut out of the sheet 10, for example, as indicated by the dotted lines in Fig. 1. Likewise a plurality of puffs may be formed substantially simultaneously from a plurality of superposed sheets such as the sheet 10. While a round puff is shown in Fig. 2, the puffs may be square. If the puffs are square the sheet 10 could be cut into strips longitudinally and laterally so as to result in a plurality of individual square puffs. In general the puffs may be any shape that is thought desirable. In making the puffs the deodorant material may be applied before the foundation member for the finished puff is cut from a large sheet or after the individual puff has been made. In either case a semi-fluid mix comprising liquid, a powdered base material and deodorant materials is made up and applied to the fibers extending from the soft and pliable foundation member as by brushing, spraying, pressure application, or the like. After the liquid has evaporated the fibers of the foundation member carry the deodorant composition 16 (as indicated by the stippling).

In Fig. 3 a puff is shown having the fibers extending from one side only. In such case the back of the puff may carry a suitable trade name 13 of any desired character, directions 14, ornaments 15 and the like, as may be desired, and all of which may be referred to generally as legends.

In Fig. 4 a modified form of puff embodying this invention is shown. In this case, a foundation member 17 is employed having fibers 18 extending from both sides thereof. The deodorant material 19 (indicated by the stippling) is, however, carried on one side only of the puff. This is advantageous as the fiber on the back of the puff which does not carry the deodorant material 19 can be used either to wipe off the skin before the deodorant is applied or to smooth over the deodorant after it has been applied from the other side of the puff.

In Fig. 5 a further modification is shown which is similar to that described in connection with Fig. 4 in that the foundation member 17 has fibers 18 extending from both sides thereof. However, in Fig. 5 the deodorant material 19 is applied to both sides of the puff. This construction is ad-

vantageous when a maximum of deodorant is to be carried on a single puff.

Deodorant puffs embodying this invention can be made of any suitable color and the color may be applied to the foundation member of the puff or to the materials adherent thereto, namely, the powdered base material or the deodorant material or both. In such case flesh tints can be had as may be desired by the user. Likewise the deodorant puff can be caused to carry perfume.

While this invention has been described in connection with certain specific embodiments thereof, it is to be understood that this has been done solely for the purpose of illustration and that the scope of the invention is to be governed by the language of the following claims.

I claim:

1. A deodorant puff which comprises a foundation member of soft and pliable material having numerous fibers extending from at least one side thereof, a powdered base material and a deodorant material; said deodorant material being coated upon said powdered base material and said powder base material as coated with said deodorant material being carried by said fibers so as to be readily detachable from said fibers upon applying said puff to the skin.
2. A deodorant puff which comprises a foundation member of soft and pliable material having numerous fibers extending from at least one side thereof, a powdered base material and a deodorant material, part of said deodorant material being carried as a coating on said powdered base material and part of said deodorant material being in the form of discrete particles carried by said fibers, said powdered base material coated with said deodorant material and said discrete particles of deodorant material being readily detachable from said fibers upon applying said puff to the skin.
3. A deodorant puff which comprises a foundation member of soft and pliable material having numerous fibers extending from at least one side thereof and carried by said fibers a powdered base material and a deodorant material, said powdered base material including a material selected from the materials calamine and zinc oxide.
4. A deodorant puff which comprises a foundation member of soft and pliable material having numerous fibers extending from at least one side thereof and carried by said fibers a powdered base material and a deodorant material, said powdered base material comprising calamine in major proportion.
5. A deodorant puff which comprises a foundation member of soft and pliable material having numerous fibers extending from at least one side thereof and carried by said fibers a powdered base material and a deodorant material, said deodorant material comprising a substance adapted to remove odor from perspiration and another substance adapted to decrease normal perspiration when applied to the skin.
6. A deodorant puff which comprises a foundation member of soft and pliable material having numerous fibers extending from at least one side thereof and carried by said fibers a powdered base material and a deodorant material, said powdered base material including in major proportion a material selected from the materials calamine,

zinc oxide and mixtures thereof, and said deodorant material including an albumen precipitant which is not injurious to silk and a substance selected from the group benzoic acid, benzoin salicylic acid and mixtures thereof.

7. A deodorant puff which comprises a foundation member of soft and pliable material having numerous fibers extending from at least one side thereof and carried by said fibers a powdered base material and a deodorant material, said powdered base material including in major proportion a material selected from calamine, zinc oxide and mixtures thereof and said deodorant material including a substance selected from the group benzoic acid, benzoin and salicylic acid, a substance selected from the group tannic acid and salts of tannic acid, and a substance selected from the group aluminum sulphate, zinc sulphate, and zinc sulpho-carbolate and oxyquinolin sulphate.

8. A deodorant puff which comprises a foundation member of soft and pliable material having numerous fibers extending from at least one side thereof and carried by said fibers about 70% to about 90% of a substance selected from the substances calamine, zinc oxide and mixtures thereof; about $\frac{1}{2}\%$ to about 5% of a substance selected from the substances benzoic acid, benzoin, salicylic acid, and mixtures thereof; and about 2% to about 15% of a substance selected from the substances tannic acid, tannic acid, salts, zinc sulphate, zinc sulpho-carbolate, aluminum sulphate, oxyquinolin sulphate, and mixtures thereof.

9. A method of making a deodorant puff which comprises making a semi-fluid paste mixture comprising a volatile liquid, a powdered base material and a deodorant material, applying the mixture to fibers extending from a foundation member of the puff, and causing the liquid to evaporate.

10. A method of making a deodorant puff which comprises making a semi-fluid mixture comprising a volatile liquid, a powdered base material undissolved in said liquid, and a deodorant material which is at least partially dissolved in said liquid, applying the mixture to a foundation member of the puff, and causing the liquid to evaporate.

11. A method of making a deodorant puff which comprises making a semi-fluid mixture comprising a volatile liquid, powdered base material undissolved in said liquid and deodorant material part of which is dissolved in said liquid and part of which is in the form of discrete particles undissolved in said liquid, applying said mixture to fibers extending from a foundation member of the puff, and causing the liquid to evaporate.

12. A method of making a deodorant puff which comprises making a semi-fluid mixture comprising a powdered base material, a water soluble deodorant material, a water-insoluble deodorant material, water and a volatile solvent for said water-insoluble deodorant material, said powdered base material being substantially insoluble in said water and said solvent being present in an amount adapted to dissolve part but not all of said water-insoluble deodorant material, applying said mixture to fibers extending from a foundation member of the puff, and causing the water and solvent to evaporate.
